TOOL FOR APPLYING BANDS TO CONDUITS

Charles G. Cooper, San Francisco, Calif.

Application September 12, 1952, Serial No. 309,343

3 Claims. (Cl. 81—9,3)

The present invention relates to improvements over the band-winding tool disclosed in my copending application, Serial No. 168,470, filed in the United States Patent Office on June 16, 1950, and now abandoned.

An object of this invention is to provide a tool for applying a strip-like band to a conduit, regardless of the width of the band. For example, the applied band may form a clamp for securing a coupling member to a hose; and, although the width of this band may vary in accordance with the requirements, the tool still may be used for applying the band.

More particularly described, it is herein proposed to provide a tool adapted for wrapping a strip-like band around a conduit with facility and ease, with the band overlapping itself. The band is firmly held in place while the layers of the overlapped portions are secured together.

As a still further object, it is proposed to utilize a strip-like band having a preformed offset extending lengthwise thereof, with this offset defining a groove in one face of the band and a projecting rib on its opposing face. In this connection, the tool is provided with band-embracing jaws, which have ribs arranged to enter the grooves of the band to thereby guide the jaws as the latter are rotated about the conduit during the application of the band, forcing the rib of one layer of the band into the groove of the adjacent underneath layer.

Moreover, it is proposed to provide a tool of the character described, which is simple in construction, durable and efficient for the purpose intended.

Other objects and advantages will appear as the specification continues. The novel features will be set forth in the claims hereunto appended.

Drawings

For a better understanding of this invention, reference should be had to the accompanying drawing, forming part of this application, in which:

Figure 1 is a side elevation view of my band-applying tool, with the jaws thereof separated and positioned on opposing sides of a conduit, and illustrating a band partially wrapped around the latter;

Figure 2 is a similar view, but disclosing the band completely wrapped about the conduit;

Figure 3 is a top plan view of Figure 2;

Figure 4 is a vertical transverse sectional view taken along the plane IV—IV of Figure 1;

Figure 5 is an enlarged longitudinal sectional view taken along the line V—V of Figure 2; and

Figure 6 is a perspective view of the strip-like band that I employ.

While I have shown only the preferred form of my invention, it should be understood that various changes, or modifications, may be made within the scope of the annexed claims, without departing from the spirit thereof.

Detailed description

Referring now to the details, I have shown a conduit indicated generally at A, which may be a hose by way of illustration. Moreover, a coupling member B has been selected for purpose of disclosure, with its tubular sleeve 10 telescoped into the bore 11 of the conduit. Of course, I do not desire to be limited to such a conduit and coupling member.

It will be noted that I provide a band-clamp C, which is fashioned from a metallic strip 12 of the shape shown in Figure 6. This strip is preformed with an offset ex-

2

tending lengthwise thereof, with this offset defining a groove 14 in one face thereof and a projecting rib 15 on its opposing face.

Upon wrapping the band strip 12 around the conduit 5 A, the rib 15 is placed against this conduit. As the strip is wrapped until it overlaps itself, as shown in Figures 2 and 5, the rib 15 of one layer enters the groove 14 of the adjacent underneath layer of the band.

In Figures 1 and 6, the end 12a of the band strip has 10 been disclosed as having a series of projections 16, which may be pressed into the wall of the conduit A. This will prevent the band from slipping relative to the conduit as the band strip is wrapped around the latter.

After the strip has been completely wrapped about 15 the conduit A, a punch may be utilized to make holes through the strip near the free end 12b thereof so that a staple 17 may be driven through the layer of the band strip and into the wall of the conduit. It will be appreciated, of course, that a small nail, screw, or other suitable fastening means may be employed for anchoring the strip in place.

In the event that the staple 17 is used, the legs 17a 20 may be long enough so as to strike the tubular sleeve 16, and thereby cause the lower ends of these legs to spread in opposite directions, as suggested by the dot-dash lines in Figure 2. The cross-bar 17b of the staple 25 may be accommodated in the groove 14 of the outermost layer of the band strip (see Figure 3).

As shown in Figures 1 to 4, inclusive, my band-applying tool includes a pair of coacting jaws D and E, which 30 are adapted to be positioned on opposing sides of the conduit A, with the strip 12 being interposed between the jaws and the conduit. It will be seen that the jaws D and E are fashioned with concaved inner faces 18 and 35 19, respectively, which confront one another and are adapted to embrace the band strip 12 when the jaws are moved toward each other.

Moreover, the confronting faces 18 and 19 of the two 40 jaws are provided with vertically-arranged ribs 20 and 21, respectively, which project therefrom and are located to enter the outermost groove 14 of the band strip. This construction will guide the jaws as the tool is swung in a counter-clockwise direction about the axis of the conduit A, thus retaining these jaws against slipping laterally as they are rotated around the conduit. As clearly 45 shown, these ribs extend lengthwise of their respective jaws; and, accordingly, will be disposed circumferentially relative to the interposed conduit. Moreover, the rib 20 on the fixed jaw D extends adjacent to, beneath and 50 beyond the lower end of the rib 21 on the movable jaws E. Both ribs are disposed in the same plane (see Figure 4).

In order to accommodate the tool to different widths 55 of band strips, the concavity of each band-embracing face is uniform from its rib to the opposing lateral sides 22 of the jaws D and E. Thus the strip 12 may extend beyond the jaw sides without obstruction. This is an important structural feature of the tool.

For the purpose of guiding the jaws toward and away 60 from one another, the jaw D has been made with a bar-like portion 23, which extends through a bifurcated lower end 24 of the movable jaw E (see Figure 4). A lug 25 projects upwardly from the outer end of the bar-like portion 23, and has a rod 26 threaded therethrough. 65 The inner end of this rod has a head 27 thereon, which is rotatably anchored in a socket 28 formed in the inner face of the jaw E (see Figures 1 and 4).

In order to turn the rod 26, and thereby advance or 70 retract the jaw E relative to the jaw D, a handle 29 is fixed to the outer end of this rod. Furthermore, this handle may be utilized for swinging both of the jaws axially around the conduit A to wrap and compress the strip thereagainst (see Figure 2). Of course, the jaws D and E may be moved toward each other by merely 75 turning the screw 26 as the band strip is applied so as to place the latter under the desired compression.

Subsequently, the legs of the staple 17 may be driven 80 through holes punched in the superimposed layers of the band strip. Both the steps of punching these holes and driving the staple may be facilitated by placing the flat underneath surface 23a of the bar-like portion 23 against

a support 30 (see Figure 2). Thus the jaw D is made to serve as an anvil.

The jaws D and E have free upper ends 31, which are separated from one another when these jaws embrace the clamp band C, thereby providing a space through which the fastening means, such as the staple 17, may be inserted to anchor the wrapped band to the conduit. It will be noted that the upper end of the jaw E is fashioned with a notch 32 therein to permit a staple, or the like, to be inserted between the jaws when the latter are applied to relatively small conduits.

Summary

The operation of my tool for applying a band to a conduit is summarized briefly as follows:

Assuming that the tubular sleeve 10 has been inserted into the bore 11 of the conduit A, then the strip 12 is wrapped partially around the conduit, with the projections 16 being pressed into the wall of the conduit to prevent the strip from slipping and with the rib 15 facing toward the conduit. Now the conduit and partially-applied band strip are introduced between the jaws D and E in the manner illustrated in Figure 1.

Next, the handle 29 is rotated so that its screw 26 will draw the jaws up against the strip. By revolving the entire tool about the axis of the conduit A in a counter-clockwise direction in Figures 1 and 2, the band strip will be wrapped tightly upon the conduit, the ribs 20 and 21 of the jaws riding along the groove 14 of the strip to thereby guide the jaws as they move around the conduit.

After the band strip has been wrapped, as shown in Figure 2, the bar-like portion 23 of the jaw D may be placed against a suitable support 30, and punch holes made through the superimposed layers of this strip. Thereupon, the legs 17a of the staple 17 may be driven through these holes to anchor the strip in final position upon the conduit, with the cross-bar 17b of the staple being accommodated in the groove 14 of the band strip.

Thereafter, the tool may be released from the conduit A and the applied band-clamp C by merely turning the handle 29 so as to separate the jaws D—E, and then disengaging the tool. Quite obviously, these jaws have been shaped to accommodate conduits of various sizes and band strips of different widths.

I claim:

1. In a tool for applying a strip-like band of the char-

acter described to a conduit: a pair of coacting jaws having concaved band-embracing faces disposed in confronting relation with each other; means for moving these jaws toward and away from one another, and for rotating the jaws about a conduit; each jaw being provided with a vertically-arranged rib on its concaved face, which projects therefrom towards the other jaw; the ribs extending lengthwise of their respective jaws; and both ribs being disposed in the same plane.

2. In a tool for applying a strip-like band of the character described to a conduit: a pair of coacting jaws having concaved band-embracing faces disposed in confronting relation with each other; means for moving these jaws toward and away from one another, and for rotating the jaws about a conduit; each jaw being provided with a vertically-arranged rib on its concaved face, which projects therefrom towards the other jaw; the ribs extending lengthwise of their respective jaws; both ribs being disposed in the same place; each jaw having opposing lateral sides between which its rib is arranged; and the concavity of each band-embracing face being uniform from the rib thereon to the opposing lateral sides of its jaw.

3. In a tool for applying a strip-like band of the character described to a conduit: a pair of coacting jaws having concaved band-embracing faces disposed in confronting relation with each other; means for moving these jaws toward and away from one another, and for rotating the jaws about a conduit; each jaw being provided with a vertically-arranged rib on its concaved face, which projects therefrom towards the other jaw; the ribs extending lengthwise of their respective jaws; both ribs being disposed in the same place; one of the jaws being slidably guided for rectilinear movement on the other jaw; the rib on the latter jaw extending adjacent to, beneath and beyond the lower end of the rib on the slideable jaw.
